LLOYD H. KINNEY, OF SCRANTON, PENNSYLVANIA.

RAIL-JOINT.

1,249,116.

Specification of Letters Patent. Patented Dec. 4, 1917.

Application filed October 29, 1915. Serial No. 58,630.

To all whom it may concern:

Be it known that I, LLOYD H. KINNEY, a citizen of the United States, residing at Scranton, in the county of Lackawanna and 5 State of Pennsylvania, have invented certain new and useful Improvements in Rail-Joints, of which the following is a specification.

My present invention relates to a new and 10 improved rail joint; and the primary object thereof is to provide a device of this nature that eliminates the use of bolts and other analogous fastening elements such as are now generally employed to retain the splice 15 bars in position, by the substitution of novel means for locking the splice bars in binding engagement with the end portions of the adjacent rails so as to effectually prevent longitudinal movement of the rails and obviate 20 the slight vertical movement at the ends thereof during the passage of rolling stock thereover.

A further object of my invention is to 25 provide a device of the type in question that is extremely simple in construction, strong and durable, and highly practical from both the standpoint of the manufacturer and the 30 standpoint of the user; and which, it is believed, may be manufactured at a minimum cost.

Various other objects and advantages will 35 become apparent during the continuance of the following description.

These objects are accomplished by such 40 means as are shown in their preferred form in the accompanying drawings, described in the following specification and then more specifically pointed out in the appended claims.

45 In the accompanying drawings wherein like characters designate like parts throughout the several views;

Figure 1 is a view in top plan showing my invention, as in its preferred embodiment, 50 in connection with a pair of rails of substantially the conventional form.

Fig. 2 is a cross sectional view taken on line 2-2 of Fig. 1.

Fig. 3 is a similar view taken on line 3-3 55 of Fig. 1.

Fig. 4 is a horizontal sectional view taken on line 4-4 of Fig. 3.

Fig. 5 is a view in perspective of one of the improved splice bars, and

55 Fig. 6 is a similar view of another of the splice bars.

In the drawings A and B designate the rails in connection with which my improved joint is shown, which are of substantially the conventional form.

In reducing my invention to practice, I 60 provide a pair of splice bars 10 and 11 that are of a construction whereby they may be arranged intimately with the side walls of the web portion of the rails, as clearly shown 65 in Figs. 2 and 3. To assure a more secure connection between the splice bars and the rails irrespective of that means hereinafter described, I provide the web portions of each of the rails with through openings 12 70 to accommodate studs 13 on the splice bar 10, while the inner face of the other splice bar has a longitudinally extending recess 14 for receiving the projecting ends of the 75 studs. I further provide the splice bars 10 75 and 11 with lateral flanges 15 and 16 which are designed to fit snugly upon the upper face of the base flange of the respective rails and to be bent to extend therebeneath, such as will be hereinafter fully pointed out.

The flange 15 of the splice bar 10 is 80 formed into a chair portion 17 to engage with the under faces of the base flanges of the rails, as shown in Fig. 1, while this chair portion is also provided with a horizontally 85 projecting ear 18 (see Fig. 5), which extends laterally of and engages with one of the base flanges and projects slightly beyond the outer edge of the base flange at a certain point, as shown in Fig. 3. The chair 90 portion 17 is further provided upon its under face with a diagonally extending rib or offset 19 that serves in the capacity of a locking device such as will be hereinafter 95 fully pointed out. The other flange 16, which is carried by the splice bar 11, is also formed to extend beneath the base flanges of the rails, in the form of a retaining flange 20, the latter being provided with a diagonally extending groove or cut-out 21 100 for receiving the rib or offset 19 of the chair 17, as shown in Figs. 2 and 3. The flange 20 is cut away adjacent one end (see Fig. 4) to receive the projecting ear 18 of the chair 17 and further provided with a 105 groove 22 to receive the projecting end of the ear as clearly shown in Fig. 3.

With a view of providing means to positively and effectually lock the splice bars against displacement after they have been 110 moved into a position to create a binding action between the rib or offset 19 and the

groove 21, I provide the ear 18 with a series of spaced openings 23 and the flange 16 with openings 24, certain of which may be brought into alignment at different times in order to receive a locking pin 25.

In the operation of my device, the splice bar 10 is first positioned in connection with the rails A and B so that the studs 13 project through the openings 12 in the webs of the rails and the chair portion 17 snugly engages the base flanges thereof. When the splice bar 10 is in this position the other bar 11 may be moved in connection with the rails so that the rib or offset 19 of the chair portion 17 engages in the groove or cut-out 21 of the retaining flange 20. The splice bar 11 is now moved longitudinally with respect to the rails to be brought into opposite alignment with the other splice bar 10 and consequently during such movement a wedging action will be exerted between the rib or offset 19 and the groove or cut-out 21 which will have a tendency to draw the splice bars and the flanges 15 and 16 into snug fitting engagement with the web and base flange respectively of the rails as is obvious. After the splice bars have been securely locked in this manner it will be found that certain of the openings 24 of the flange 16 will register with certain of the openings 23 of the ear 18 of the chair portion, consequently permitting the insertion of the locking pin 25 in order to prevent retrograde movement of the splice bar 11. As wear upon the web portion of the rails continues the locking pin 25 may be removed so that the splice bar 11 may be again moved longitudinally with respect to the rails so that the rib 19 operating in the cut-out 21 will tend to draw the bars toward each other and thus compensate for such wear of the web. It will be found that this adjustment will bring other of the openings 23 and 24 into alignment such as will permit the reinsertion of the locking pin 25.

From the foregoing it will be noted that the splice bars are readily adjustable so as to have snug fitting engagement with the web portion of the rails at all times and thus effectually retain the rails both against longitudinal movement as well as slight vertical movement. The splice bar 11 may be driven with a sledge so that an efficient binding action will be exerted through the cooperation of the rib 19 and the cut-out 21 whereas it may be also locked against retrograde movement after having reached a position whereby the desired tension is exerted on the web portion of the rails. It is believed that the advantages and other novel features of my invention will be readily understood and therefore further detailed description is deemed unnecessary. In reducing my invention to practice I find that the form referred to herein as the

most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is;

1. A rail joint for connecting the meeting ends of a pair of railway rails comprising a splice bar formed with a chair portion to engage and support the rails and also formed with a downwardly extending element and a laterally extending element, the latter being provided with a row of apertures; a second splice bar formed with means for coöoperating with the downwardly extending element of the first said splice bar to draw said bars toward one another when they are adjusted longitudinally, said second splice bar being formed with a recess to receive the laterally extending element of the first said splice bar, said second splice bar being also formed with a row of apertures; and means insertible through aligned apertures of said rows so as to retain said splice bars in different adjusted positions with relation to one another.

2. A rail joint for connecting the meeting ends of a pair of railway rails comprising a splice bar formed with a chair portion to engage and support the rails and also formed with a downwardly extending element and a laterally extending element, the latter projecting outward beyond the edge of the base flange of the rail when it is supporting the latter; a second splice bar formed with means for coöoperating with the downwardly extending element of the first said splice bar to draw said bars toward one another when they are adjusted longitudinally, said second splice bar being recessed to receive the portion of said laterally extending element that projects beyond the base flange of the rail and also being provided with an aperture that establishes communication between the recess and the upper surface of the bar; and means coöperative with the apertured portion of the said second splice bar and with the said laterally extending element of the first said splice bar to hold these splice bars in different adjusted positions with relation to one another.

3. In a rail joint of the character described, the combination with a pair of rails, of a pair of splice bars to be associated with the webs of said rails, means carried by one of said splice bars to prevent longitudinal movement of said rails with respect to each other, said splice bars being provided with

lateral flanges to engage with the upper face of the base flange of said rails, one of said flanges being formed into a chair portion to engage with the under face of the base flanges of said rails, a diagonally extending rib formed on the under face of said chair portion, said chair portion being provided with a laterally projecting ear adjacent one end, said ear provided with a series of receiving openings, a retaining flange formed on the other of said first mentioned flanges to engage with the under face of said chair portion, said retaining flange provided with a diagonally extending cut-out to receive said rib, said retaining flange

being cut away at one end to receive said ear, one of said first mentioned flanges provided with openings which may be brought into register with the openings of said ear at certain times and a locking pin to be positioned through the registering openings to prevent movement of said splice bars longitudinally with respect to each other, as and for the purpose specified. 20

In testimony whereof I affix my signature 25
in presence of two witnesses.

LLOYD H. KINNEY.
